(57) **CLAIM**

The ornamental design for an automobile rear portion as shown and described.

DESCRIPTION

FIG. 1 is a front perspective view of the automobile rear portion showing my design;

FIG. 2 is a rear perspective view thereof;

FIG. 3 is a front elevation view thereof;

FIG. 4 is a right-side view thereof;

FIG. 5 is a rear elevation view thereof;

FIG. 6 is a top plan view thereof; and,

FIG. 7 is a bottom view thereof.

Portions of the automobile rear portion and surrounding portions of an automobile shown in broken lines form no part of the claimed design.
